UNITED STATES PATENT OFFICE.

WILLIAM EDWIN WILLIAMS, OF DECATUR, TEXAS.

CULTIVATOR.

SPECIFICATION forming part of Letters Patent No. 469,109, dated February 16, 1892.

Application filed August 8, 1891. Serial No. 402,132. (No model.)

To all whom it may concern:

Be it known that I, WILLIAM EDWIN WILLIAMS, a citizen of the United States, residing at Decatur, in the county of Wise and State of Texas, have invented certain new and useful Improvements in Cultivators; and I do hereby declare the following to be a full, clear, and exact description of the invention, such as will enable others skilled in the art to which it applies to make and use the same.

My invention consists in a new and improved cultivator in which are combined many novel and valuable features, and the invention will be hereinafter fully described and claimed.

Referring to the accompanying drawings, Figure 1 is a perspective view of my new and improved cultivator. Fig. 2 is a detail side elevation of parts of the cultivator. Fig. 3 illustrates in detail, on an enlarged scale, the bearing-blocks and couplings at the rear ends of the connecting-rods. Fig. 4 illustrates in detail, on an enlarged scale, the bearing-blocks and couplings at the forward end of the connecting-rods. Fig. 5 illustrates in detail, on an enlarged scale, the spring-couplings of one of the cultivator-blades.

Referring to the several parts by their designating-numerals, 11 indicate the side pieces of the main frame of the cultivator, which are provided each with the three upwardly-projecting bearing-pins 1^a. From the sides of the frame-pieces 1 extend outwardly the stub-axes 2, on which the supporting-wheels 3 of the machine are mounted.

4 indicates the rear cross-beam, and 4^a the front cross-beam, of the cultivator-frame, each of the said beams being mounted on the end pieces 5, the lower ends of which are formed with the vertical bearings 6 to adapt them to fit on the bearing-pins 1^a of the frame sides.

The forward ends of the side pieces 1 are provided with the inwardly-extending bars 7, each of which is formed with a longitudinal horizontal slot 8. Upon each bar 7 is adjustably mounted a bearing-block 9, having a central space 10 to adapt it to fit snugly on its bar 7. This coupling-block is held in place by means of a flanged retaining-block 11, fitting in the rear side of the slot and held in that position by the side pieces 12^a of the hooked frame 12. These side pieces extend

through the coupling-blocks from the front side of the same through the longitudinal slot 8 and through the flanged block 11 and have 55 nuts screwed upon their threaded inner ends. By loosening these nuts the coupling-blocks can be moved nearer together or farther apart to regulate the space between the cultivator-blades.

13 13 indicate the rear coupling-blocks, to which the shovel-standards are attached. On the top of each of these blocks are formed the parallel ears 15, and at the rear upper ends of the front blocks 9 are formed the parallel ears 65 14. Between the ears 14 and 15 on the rear and front coupling-blocks are pivoted on horizontal pivot-bolts the coupling-links 16, which are precisely similar in construction, each one being formed with a horizontal bearing 16^a 70 and a vertical bearing portion 16^b. These vertical bearings 16^b are pivoted in bearings 17^a, formed at the ends of the upper connecting-bars 17. At the lower ends of the front and rear coupling-blocks 9 13 are formed the bearings 18, in which are pivoted on the horizontal pivot-bolts 19 the metal bearing-plates 20, which are formed at their outer ends with the end bearings 21. The ends of these plates 20 are pivoted by vertical pivot-pins in the bearings 22^a, formed at the ends of the lower connecting-rods 22.

From the above description, taken in connection with the accompanying drawings, it will be seen that the peculiar pivotal connection between the front supporting-bars 7 and the standards of the cultivator-blades will enable the said standards to move to either side, the connecting-rods turning on their vertical end pivots. Upon the front cross-beam are mounted the hand-levers 23, having spring-catches, which are adapted to engage with the teeth of the curved racks 24, and the lower projecting ends of these levers are connected by chains 25 with the upper connecting-rods 90 17. It will be seen that by means of these levers the rear coupling-blocks, and consequently the cultivator standards and blades, can be raised or lowered, the horizontal pivots of the links 16 and plates 20 permitting 95 100 the said parts to turn freely to admit of this movement.

26 indicates springs, which are mounted in the rear coupling-blocks, as shown, and which

are so arranged as to bear upon the pivoted links 16 and plates 20, so that while the rear coupling-blocks have a slight independent movement as the cultivator passes over uneven ground these springs will serve to automatically return the cultivator-blades to their normal operative position.

To the lower end of the standards are secured the foot-pieces 27, having the curved lower ends, as shown. To the lower ends of each foot-piece are centrally pivoted the short curved levers 28, upon the lower end of which a cultivator-blade is mounted. To the rear end of the levers 28 are pivoted the lower ends of flat links 29, 29, the upper ends of which are pivoted to the levers 30 30. These levers are pivoted near their upper ends to the stem or foot-piece 27, and their upper ends project to the rear of said stem. A coiled spring 31 is secured at its upper end to the rear ends of the levers 30 and at its lower end to a fixed projection 32, affixed to the lower end of the stem 27. The upper ends of the links 29 are connected by a stirrup 33, which extends around the front of the stem 27. It will be seen that by this construction when one of the cultivator-blades strikes against a stone or other immovable obstruction the blade will fly back, as illustrated by dotted lines in the detail view, Fig. 2, the various connecting links and levers turning, as shown in that view, and as soon as the obstruction is passed the spring 31 will press the parts back to their normal operative position. It will be seen that this construction will effectually prevent the cultivator-blades from being broken and will immediately restore them again to their operative position as soon as an obstruction is passed.

34 indicates the tongue, which is more properly the connecting-reach, as the horses are hitched to the hooks 12. The rear end of this tongue or reach is secured by a pivot-bolt 45 upon the center of the rear cross-beam 4, while its forward end passes between the front beam 4^a and the transverse bar 35, to which the upper half of the fifth-wheel is secured. When the cultivator is used as a riding-cultivator, 50 the wheel 36 is secured upon the rear part of the reach 34, and the rear cross-beam 4 is arranged as shown in Figs. 1 and 2; but when it is used as a walking-cultivator the reach is slid forward until the king-bolt can be passed 55 through a central aperture 37 in the reach, and the apertured lower ends of the rear beam-supports are seated on the metal bearing-pins 1^a, thus giving sufficient room for the handles, which are used when the cultivator is arranged as a walking-cultivator.

It will be seen that as the ends of the cross-beams are pivotally or movably mounted on the side pieces of the cultivator-frame, and as the reach 34 is pivotally connected to the front 65 and rear cross-beams 4^a 4, the entire machine-frame will give or turn to either side to assist in turning at the end of a row, the extent of

this movement being limited by stop-pins 38, which pass down vertically through the halves of the fifth-wheel on each side of the forward end of the connecting-reach 34.

From the foregoing description, taken in connection with the accompanying drawings, it is thought that the construction and operation of my new and improved cultivator and the advantages of the many novel features embraced therein will be clearly understood without requiring further detailed description.

Having thus described my invention, what I claim, and desire to secure by Letters Patent, is—

1. In a cultivator, the combination of the forward coupling-blocks 9, formed at their rear ends with the upper bearings 15 and the lower bearings 18, the rear coupling-blocks 13, to which the cultivator-standards are secured, formed at their upper ends with the bearings 14 and at their lower ends with the bearings 18, the coupling-links 16, and the bearing-plates 20, arranged as specified, the upper connecting-bars 17, pivotally connected at their ends with the coupling-links 16, and the lower connecting-rods 22, pivotally connected at their ends to the pivoted bearing-plates 20, all substantially as set forth.

2. In a cultivator, the combination of the forward coupling-blocks 9, formed at their rear ends with the upper bearings 15 and the lower bearings 18, the rear coupling-blocks 13, to which the cultivator-standards are secured, formed at their upper ends with the bearings 14 and at their lower ends with the bearings 18, the coupling-links 16, and the bearing-plates 20, arranged as specified, the upper connecting-bars 17, pivotally connected at their ends with the coupling-links 16, and the lower connecting-rods 22, pivotally connected at their ends to the pivoted bearing-plates 20, the pivoted hand-lever 23, and the chains 25, connecting said levers with the upper connecting-bars 17, substantially as and for the purpose set forth.

3. In a cultivator, the combination of the forward coupling-blocks 9, formed at their rear ends with the upper bearings 15 and the lower bearings 18, the rear coupling-blocks 13, to which the cultivator-standards are secured, formed at their upper ends with the bearings 14 and at their lower ends with the bearings 18, the coupling-links 16, and the bearing-plates 20, arranged as specified, the upper connecting-bars 17, pivotally connected at their ends with the coupling-links 16, and the lower connecting-rods 22, pivotally connected at their ends to the pivoted bearing-plates 20, and the springs 26, arranged, as specified, to act upon the pivoted links 16 and plates 20, substantially as and for the purpose herein set forth.

4. In a cultivator, the combination of the side pieces 1, having at their forward ends the inwardly-extending bars 7, formed with the longitudinal horizontal slots, the forward

adjustable coupling-blocks 9, adapted to fit on the slotted bars 7 and connected with the cultivator-standards, the flanged retaining-blocks 11, fitting in the rear sides of the longitudinal slots 8, and the rods 12^a, passing through the coupling-blocks and the retaining-blocks and having the nuts on their threaded rear ends, substantially as set forth.

5. In a cultivator, the combination of the side frame-pieces 1, each of which is provided with three vertical bearing-pins 1^a, the front and rear cross-beams having the end bearings removably fitting on said pins, and the adjustable reach 34, pivotally connected to 10 the front and rear cross-beams, substantially as set forth.

6. In a cultivator, the combination of the

stems 27, the levers 28, centrally pivoted to the lower ends of said stems and carrying the cultivator-blades at their lower ends, the levers 30, pivoted to the stem 27, the links 29, connecting the lower ends of said levers to the upper ends of the blade-levers 28 and having the stirrups 33 at their upper ends, and the springs 31, attached to the upper ends 25 of the levers 30, and the fixed point on the stem 27, substantially as and for the purpose set forth.

In testimony whereof I affix my signature in presence of two witnesses.

WILLIAM EDWIN WILLIAMS.
